ATTORNEYS

UNITED STATES PATENT OFFICE.

CECILIA D. McVAY, OF PHILADELPHIA, PENNSYLVANIA.

PHONOGRAPHIC-DISK-RECORD CABINET.

1,302,943.

Specification of Letters Patent.

Patented May 6, 1919.

Application filed December 2, 1916. Serial No. 134,568.

To all whom it may concern:

Be it known that I, CECILIA D. McVAY, a citizen of the United States, residing in the city and county of Philadelphia, State of Pennsylvania, have invented a new and useful Improvement in Phonographic-Disk-Record Cabinets, of which the following is a specification.

In my prior Patent Number 1,219,975 of Mar. 20, 1917, of which the present invention in its broad aspects is somewhat similar, I have shown, described and claimed a novel construction of phonographic disk record cabinet, wherein the record receiving compartments are arranged horizontally and superimposed above each other, each of said compartments being provided with a suitable ejecting lever. In my present invention, I have shown my device as provided with operating devices for ejecting the records located at the front of the cabinet, the broad principle disclosed in my previous application aforesaid being employed, in so far as regards the location and correlation of the horizontal record-receiving compartments and their ejector devices.

To the above ends, my invention consists of the novel construction of a phonographic disk record cabinet, having horizontal compartments provided with ejector devices in the rear thereof, which are operated by means of suitable buttons located at the front of the device, thereby making the same especially adapted for insertion into talking machine cabinets of the type already upon the market.

In cabinets for the reception of flat disk records it has heretofore been proposed to arrange such disk records on their edges in rows and to provide various forms of ejecting devices for propelling the records from the cabinet.

It has been, however, found in practice that the records, particularly of the Victor and Columbia types, are sometimes liable to warp or change their shape somewhat if stood on their edges for any length of time, unless some special provision is made to prevent this, and my present invention consists of a novel construction of disk record cabinet provided with a series of horizontal partitions, whereby horizontal compartments are formed in which the records are at all times supported flat upon their sides in a lateral or horizontal plane, each compartment being provided with an individual ejector of simple con-

struction, which is pivotally supported, preferably in the rear of the horizontal compartments, one ejector lever being provided for each record or for each compartment, whereby a slight oscillation of said ejector lever by the pressure of the thumb or finger on the portion of the operating mechanism thereof protruding from the casing will serve to propel the records horizontally from the cabinet, so that they can be grasped by the fingers of the user and withdrawn therefrom.

Another advantage of my construction is that a single standard type of cabinet of my invention is applicable for the reception of records of different thicknesses. In addition, the same type of cabinet can be employed for ten-inch as well as twelve-inch records, so that it necessary to employ only a single standard size of cabinet for the reception of any or all records.

In certain cabinets of this general character which have heretofore been proposed, there has been no provision made for the ready ejection of a ten-inch record, if improperly or inadvertently placed in the larger compartment adapted for a twelve-inch record, since in such event the ejecting devices for the twelve-inch record might not be applicable to or co-operative with the ten-inch record, or vice versa, but in my novel construction the same ejector device is applicable to and efficient with records of varying thicknesses and diameters.

Figure 1 represents a front elevation partly in section of a phonographic disk record cabinet embodying my invention.

Fig. 2 represents a section on line 2-2, Fig. 1.

Fig. 3 represents a perspective view of the actuating mechanism employed.

Fig. 4 represents a perspective view of a talking machine cabinet having my invention applied thereto.

Similar numerals of reference indicate corresponding parts in the figures.

Referring to the drawings:

1 designates my novel construction of phonographic disk record cabinet, the same comprising a casing having the side walls 2 and 3, the top member 4, the back or rear wall 5 and the base and bottom member 26. The inner walls of the sides 2 and 3 are provided with the alining grooves or recesses 6, in which are inserted the horizontal shelves 7, which may incline downwardly and rear-

wardly if desired and may be made of wood, pasteboard, fiber, thin sheet metal or other material, whereby compartments 8 are formed, which may have horizontal bases, 5 (or if desired, as stated, may incline somewhat rearwardly and downwardly) in which are contained in a substantially horizontal position the flat disk records 9. It must be understood that these lateral compartments 10 may be formed in various ways other than shown.

In order to propel the records forwardly in a horizontal or lateral direction, I provide the walls 3 with a series of slots 10 through 15 each of which projects an end 11 of an ejector lever 12, there being a lever for each compartment, said levers being fulcrumed on the rod 13 and each being provided with a record engaging terminal 14 and each lever 20 having pivoted thereto at 15 a forwardly projecting link, as 16, whose outer end is pivotally or otherwise attached at 17 to the short rod 18, which carries the button or finger-piece 19, which may be provided with 25 suitable indicia.

As a guiding means, I employ preferably the upright strip 20 having the front member 21, through which the rods 18 project, the member 22 being secured to the side 3 of the cabinet in any suitable manner desired. 30 I preferably arrange the links 16, as seen in Fig. 2, so that the rods 18 and the finger-pieces 19 connected therewith extend in two vertical planes, said finger-pieces being arranged in alinement with each other or in staggered order, as will be understood from Figs. 1 and 3. If desired, the inner ends of 35 the terminals 14 can slide upon the bottoms of their respective shelves, such terminals 40 being adapted for the ejection of a thick Edison record or a thin Victor or Columbia record as is evident. I preferably locate the top end of the rod 13 in a seat or socket, as 23, in the top 4 of the cabinet, the lower end 45 of said rod 13 being stepped into a seat as 25, in the bottom or base piece 26 of the cabinet. The levers 12 can be separated from each other by means of sleeves 27, through 50 which the rod 13 passes, there being a sleeve 27 interposed between each of the levers 12, in order to properly space them, as seen from Fig. 3, although it will be apparent that said 55 levers 12 can be provided with an integral spacing sleeve or otherwise spaced apart, according to requirements.

The rearward movement of the ejector levers 12 may be limited by the contact of the portion 28 with the inner portion of the rear wall 5, while the forward movement of the 60 terminal 14 of said levers may be limited by the contact of the rear of said lever with the walls 29 of the slot 10, as is evident from Fig. 2.

It will be apparent that the insertion or 65 pushing of the records rearwardly will push

the ejector levers 12 rearwardly and their co-acting links 16, rods 18 and buttons 19 outwardly and when it is desired to use a particular record, the same can be propelled forwardly by pushing inwardly the proper button 19 and after any finger-piece has been pushed rearwardly so as to propel a record forwardly, it is apparent that said button or finger-piece will remain pushed in and thus be a telltale of the proper compartment in 75 which to replace the record. As the terminal 14 can, if desired, rest or be guided upon the top of its proper shelf 7, no guiding or supporting devices are required for the inner ends of the ejector levers 12, other than the 80 vertical fulcrum rod 13 and the support afforded by the bottom shelf in each of the compartments 8, although if desired, I may slightly weight the termini 14, so that they will at all times properly contact with the 85 bottom of their compartments.

If desired, the top portions of the shelves may be suitably lined with felt or cloth, as indicated at 30 or if it is desired to equip a portion of the cabinet, as either half, with 90 compartments especially adapted only for ten-inch records and also for twelve-inch records only, this can be readily done by inserting filler pieces 31 in the outer portions of such compartments, as are desired to be used 95 exclusively for ten-inch records, as must be understood from Fig. 1.

In the use or operation of my device, it will be apparent that the records are at all times supported flat upon their sides, so that 100 all liability of their warping or changing their contour is reduced to a minimum and the stability and life of the record is thus assured and prolonged.

It will now be apparent that I have 105 devised a novel and useful construction of a phonographic disk record cabinet which embodies the features of advantage enumerated as desirable in the statement of the invention and the above description, and while I have, 110 in the present instance, shown and described preferred embodiments thereof, which will be found in practice to give satisfactory and reliable results, it is to be understood that the same are susceptible of modification in 115 various particulars without departing from the spirit or scope of the invention or sacrificing any of its advantages.

Having thus described my invention, what I claim as new and desire to secure by Letters Patent, is:

A phonograph disk record cabinet, comprising a casing having one side open and provided with a plurality of horizontal record receiving compartments, a vertical fulcrum rod arranged within one corner of the casing near its back, horizontally swinging ejector levers arranged within the compartments and fulcrumed upon the rod and having their outer ends projecting laterally beyond 130

the casing, a guide plate arranged at a right angle to one side of the casing and attached thereto near its forward side, said guide plate having two sets of vertical openings, push 5 rods mounted to slide within the openings and extending toward the forward side of the casing, and links pivotally connected

with the push rods and with the outer ends of the ejector levers.
